WALL RADIATOR SUPPORT

Filed Feb. 20, 1926

Inventor
Anthony E. Davis

By Herbert S. Fairbanks

Attorney

UNITED STATES PATENT OFFICE

ANTHONY E. DAVIS, OF PHILADELPHIA, PENNSYLVANIA

WALL RADIATOR SUPPORT

Application filed February 20, 1926. Serial No. 89,582.

My invention relates to a novel wall radiator support and more particularly to novel means for effecting the proper alignment of the radiator.

5 In devices of this character as heretofore manufactured, the upper portion of the bar or body portion of the bracket has been laterally deflected but has not been provided with any lateral adjustment, or aligning means.

10 It is the purpose of my present invention to combine with the body portion of the bracket adjustable means to effect the alignment of the radiator.

With the above and other objects in view 15 as will more clearly hereinafter appear, my invention comprehends a novel wall radiator support provided with novel means to effect the alignment of the radiator.

It further comprehends a novel construction of an aligning member, and novel means 20 for aligning it with the bar and for securing it in its adjusted position.

Other novel features of construction and 25 advantage will hereinafter more clearly appear in the detailed description and the appended claims.

For the purpose of illustrating the invention, I have shown in the accompanying drawings a typical embodiment of it, which in practice, will give reliable and satisfactory results. It is, however, to be understood 30 that this embodiment is typical only and the various instrumentalities of which my invention consists can be variously arranged and organized, and the invention is not, therefore, limited to the precise arrangement and organization of these instrumentalities as herein set forth.

40 Figure 1 is a side elevation of a wall radiator support, embodying my invention, and assembled with respect to a wall.

Figure 2 is a top plan view of the upper portion of the support.

45 Figure 3 is a front elevation of the construction seen in Figure 2.

Figure 4 is a front elevation of another embodiment of my invention.

50 Figure 5 is a top plan view of the construction seen in Figure 4.

Similar numerals of reference indicate corresponding parts.

Referring to the drawings:

1 designates a wall radiator support, embodying my invention, and, for purpose of illustration, I have preferred to show the support, radiator, cradle and the manner in which the cradle is carried by the bar as substantially the same as that shown in my co-pending application for adjustable wall 55 radiator Ser. No. 750,727, filed November 19th, 1924, although it is to be understood that my present invention can be employed in conjunction with any desired or conventional type of radiator.

60 1 designates the supporting bar or body portion of the wall radiator support, which is adapted to be secured to a wall 2 by means of fastening devices 3.

65 A rod 4 is swivelled on the bar 1, at 5, and carries a cradle 6, having deflected apertured arms 7 and 8, between which is disposed a spacing sleeve 9. The rod 4 passes through the arms 7 and 8 and the spacing sleeve 9, and has its lower end threaded to receive a nut 10 which bears against the arm 8. 11 is the radiator.

70 The upper end of the bar 1 is laterally deflected, as at 12, and is provided with a threaded aperture 13.

75 14 designates a radiator aligning member having a slot 15 through which passes a screw 16 which engages the walls of the threaded aperture 13. The aligning member 14 is formed from sheet metal, in the form of a plate having depending side flanges 17 formed from the plate and serving as guides which overhang the sides of the arm formed by the deflected portion 12. These flanges 17 merge into the laterally extending flanges 18 which serve to reinforce the plate 14 which is provided with a slot 19 to receive the tie rod 20, of the usual construction. I have clearly shown in the drawings that the slot 19 is elongated. Due to the length of this slot, the tie rod can always be connected in proper position irrespective of the relative location of the radiator support and the columns of the radiator since the width of a radiator column is less than the length of the 80 85 90 95 100

slot. The tie has its outer end threaded and provided with a nut 21 which bears against a button 22 of any desired or conventional construction.

5 In Figures 4 and 5, I have shown another form of aligning member which can be advantageously employed, and wherein 23 designates an aligning member formed from sheet material having opposite marginal portions bent downwardly, as at 24. The member 23 has deflected out of it the downwardly extending guides 25, which overhang the arm formed by the deflected end 12 of the supporting bar 1.

15 The wall radiator support is secured to the wall in the usual manner by the bolts 3. The radiator 11 is then placed on the cradle 6, and the operator adjusts the aligning member 14 to properly align and plumb the radiator, and then tightens the screw 16. The tie rod is then applied in the usual manner so that the radiator is secured in its properly aligned position on its support.

25 My present invention is a marked advance in the art as it provides means forming a part of the bracket to effect the proper alignment of the radiator.

30 In the forms of my invention herein shown, the aligning member is accurately guided during its adjustment so that it will have the proper contact with the radiator.

Having thus described my invention what I claim as new and desire to secure by Letters Patent, is:—

35 1. In a wall radiator support, the combination with its body portion having its upper end laterally deflected, of a radiator aligning member laterally adjustable on said deflected portion and having guide members co-
40 operating with said deflected end and having a tie rod receiving slot, means to secure said member in its adjusted position and a tie rod adapted to pass through said slot.

2. In a wall radiator support, the combination with its body portion having its upper end deflected, of an aligning member having flanges to overhang said deflected end and adjustable on said end, and having a tie rod receiving slot, and means to secure said member on said deflected end in the position to which it has been adjusted.

45 3. The herein described aligning bracket for plumbing the radiator, comprising a strip of sheet metal having opposite sides downwardly deflected and provided at its rear edge with downwardly deflected flanges formed from it and forming guiding means, and having a slot between said flanges to provide for the adjustment of said bracket, said bracket having also near its forward end a laterally extending slot adapted to receive a tie rod.

4. In a support for a radiator the combination with a wall piece adapted to be secured to the wall, a radiator seating bracket

arranged to be supported on said wall piece, a substantially horizontal flange on said wall piece and an offset plate slidable upon the upper surface of said flange and adapted to be extended and retracted therefrom to form 70 an adjustable abutment for changing the position of the radiator with respect to a vertical plane.
